(57) **CLAIM**

The ornamental design for a hitch lock packaging, as shown and described.

DESCRIPTION

FIG. 1 is a perspective view of a hitch lock packaging showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken lines, which define the bounds of the claimed design, form no part thereof.

The environment shown in broken lines form no part of the claimed design.
